UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

UNCOUPLING MECHANISM.

1,417,606.

Specification of Letters Patent. Patented May 30, 1922.

Application filed October 6, 1921. Serial No. 505,723.

To all whom it may concern:

Be it known that I, WILLIAM KELSO, a citizen of the United States, residing at Pittsburgh, in the county of Allegheny and 5 State of Pennsylvania, have invented certain new and useful Improvements in Uncoupling Mechanism; and I do hereby declare the following to be a full, clear, and exact description of the invention, such as 10 will enable others skilled in the art to which it appertains to make and use the same.

My invention relates to uncoupling mechanism for moving the lock of a car coupler to unlocked position, and while it is primarily designed to afford means especially 15 well suited for use with the Master Car Builders' standard D-type coupler having a bottom operated lock, yet it may be employed with other types of couplers as well. 20 The primary object of the invention is to provide an effective and easily operated uncoupling mechanism of simple and compact form consisting of few and durable parts which may be readily assembled and 25 disassembled.

The primary feature of the invention, generally stated, consists in actuating the lock of the car coupler by means of a rotatable member which is swingingly supported so that its center of rotation may 30 shift lengthwise of the car.

A further feature of the invention consists in causing the coupler lock to be moved to an unlocked position by means of a rotatable member which is supported from the coupler carrier iron by a member which is adapted to swing lengthwise of the car to compensate for bodily movement of the rotatable member in its direction of length 40 during an unlocking rotation of the latter.

A still further feature of the invention consists in actuating the lock of the coupler through the medium of a rotatable member which is swingingly supported rearwardly 45 of the lock by means adapted to move both lengthwise and transversely of the car.

There are other features of invention residing in particular combinations and details of construction all as will hereinafter 50 appear.

In the drawings illustrating the invention, the scope whereof is pointed out in the claims,—

Figure 1 is a view, partly in side elevation

and partly in vertical section, of an uncoupling mechanism embodying the invention, the car coupler illustrated being of the well known Master Car Builders' D-type. 55

Figure 2 is a detail sectional view on the line 2—2, Fig. 1, portions of the uncoupling 60 levers which extend toward the sides of the car and of the coupler carrier iron and coupler stem being broken away.

Figure 3 is a detail sectional view on the line 3—3, Fig. 1. 65

Should it be desired to permit the coupler 1 to have a considerable swinging movement laterally of the car the rear end of the coupler shank may be formed with a pivot pin opening 2 which is adapted to receive a 70 tail pin (not shown) whereby the coupler may be pivotally connected to the draft rigging in a well known manner.

The lock 3 of the coupler is movably connected at its lower end to a link 4 which projects downwardly through the head of the coupler and which is pivotally connected at its lower end to a swinging member or lift lever 5 which is itself pivoted to the under side of the coupler head upon the knuckle 75 side thereof. The link 4 and pivoted lift lever 5 illustrated in the drawings may be and preferably are constructed and arranged in accordance with the standard practice of the bottom lock lift devices of 80 85 the D-type coupler.

Movably connected to the pivoted member 5 so as to be capable of actuating the latter to cause the lock 3 to perform an unlocking movement, such as may be necessary 90 either to unlock the knuckle or to actuate the knuckle opening device of the coupler, is a rotatable member 6 which extends rearwardly of said lock and is not only capable of rotating vertically but also, during its 95 rotation, is capable of bodily movement lengthwise of the car. To permit the member 6 to move in this manner it is swingingly supported at its center of rotation by means of a link device 7 which is adapted to 100 swing lengthwise of the car. By this means, as is shown by the dot and dash arc 8, the member 5 pivoted to the coupler head and the vertically rotatable member 6 may cooperate with each other during an unlock- 105 ing operation of the mechanism without any binding or slipping of these parts on one another such as would occur if, as indicated

by the dot and dash arc 9, the center of rotation of the member 6 were fixed. As a means for movably connecting the vertically rotatable member 6 to the pivoted member 5 carried by the coupler, said member 6 may be provided at its forward end with a hook 10 which cooperates with the eye 11 at the rear end of the member 5, the members 5 and 6 thus being interlockingly connected. 5 At its rear end the member 6 is preferably provided with oppositely disposed laterally extending trunnions or pivots 12 which are respectively received by hooks 13 forming segmental bearings for said trunnions. 10 Beneath the trunnions the member 6 is preferably provided with laterally opening recesses 14 which are respectively adapted to receive the upwardly extending ends 15 of rotatable uncoupling rods or levers 16. 15 These levers extend toward the sides of the car and preferably are of the well known form illustrated in the I. H. Milliken Patent No. 1,184,116, dated May 23, 1916.

The swinging link 7 may be conveniently 20 connected to the coupler carrier iron 17 through the intervention of a hook and eye connection, the upper end of said link being provided with a hook 18 which cooperates with an eye 19 that is formed in a coupler saddle 20 slidably mounted on the carrier iron and adapted to be shifted laterally of the car by the stem of the coupler when the latter executes an extended swinging movement. The hook and eye connection between the carrier iron and the link 7 enables the latter readily to swing both lengthwise and transversely of the car and to turn in response to the lateral angular movement of the rotatable member 6. Where the coupler 25 is intended to have a very wide range of lateral swinging movement it may be advantageous to provide for the necessary lateral movement of the link 7 by movably connecting the latter to the coupler saddle 20, as shown, rather than to support said link directly from the carrier iron.

To assemble the mechanism the swinging link device 7 is turned laterally until it is at right angles to its normal position when its hook 18 may be hooked through the laterally elongated eye 19 of the coupler saddle 20. The link 7 when dropped to ordinary position interlocks with the member 20 so that these parts cannot become accidentally disconnected. The hook 10 at the forward end of the rotatable member 6 is then hooked through the eye 11 of the pivoted member 5 carried by the coupler, after which the trunnions 12 are seated in the bearing hooks 13 at the lower end of the swinging support 7. The inner ends 15 of the uncoupling levers 16 are thereafter inserted in the respective openings 14 of the member 6 and their outer ends may be movably supported in brackets 65 at the sides of the car in the usual way. As

thus assembled the several parts are interlocked in a manner preventing their accidental disassociation.

Either of the uncoupling levers 16 may be rotated to actuate the member 6 to effect an 70 unlocking movement of the coupler lock 3, the flaring character of the openings 14 in the member 6 into which the uncoupling levers extend enabling either of said levers to be independently employed. When the 75 member 6 is caused to perform an upward vertical rotation in the act of moving the pivoted member 5 and link 4 to operate the coupler lock, its trunnions 12 rotate in the segmental bearings 13 of the swinging supporting link 7 and the latter swings lengthwise of the car as may be necessary to permit the forward end of the rotatable member 6 to conform to the path of movement of the eye 11 at the rear end of the pivoted member 80 5, thus enabling the unlocking and knuckle throwing operations of the coupler to be accomplished with a minimum expenditure of effort upon the part of the trainman.

I claim:—

1. In an uncoupling mechanism, the combination with a car coupler, its lock and carrier iron, of means for moving said lock to unlocked position, said means involving a rotatable member operatively connected to 95 said lock and extending rearwardly therefrom, an uncoupling lever, and means for swingingly supporting the rear end of said rotatable member from said carrier iron, said supporting means being adapted to 100 swing lengthwise of the car in response to lengthwise bodily movement of said rotatable member during its unlocking rotation, and said rotatable member being interposed between said uncoupling lever and said supporting means.

2. In an uncoupling mechanism, the combination with a car coupler and its lock, of means for moving said lock to unlocked position, said means involving a rotatable member operatively connected to said lock and extending rearwardly therefrom, an uncoupling lever, and means adapted to swing lengthwise of the car for supporting the rear end of said rotatable member, said rotatable member during its rotation being adapted to force said supporting means to swing in compensation for bodily movement of said rotatable member in its direction of length, and said rotatable member being interposed between said uncoupling lever and said supporting means.

3. In an uncoupling mechanism, the combination with a car coupler and its lock, of means for moving said lock to unlocked 125 position, said means involving a rotatable member operatively connected to said lock and extending rearwardly therefrom, an uncoupling lever, and a link device for supporting the rear end of said rotatable mem- 130

ber, said link device being adapted by swinging lengthwise of the car to compensate for bodily movement of said rotatable member in its direction of length during an unlocking rotation of said member, and said rotatable member being interposed between said uncoupling lever and said link device.

4. In an uncoupling mechanism, the combination with a car coupler and its lock, of means for moving said lock to unlocked position, said means involving a swinging member pivotally connected to said coupler, a link interposed between said swinging member and said lock, a rotatable member operatively connected to said lock and extending rearwardly therefrom, an uncoupling rod extending toward the side of the car and adapted to cause said rotatable member to perform an unlocking rotation, and swinging means directly supporting said rotatable member at its rear end; said last named means being adapted to swing lengthwise of the car in response to bodily movement of said rotatable member in its direction of length during an unlocking rotation of said member.

5. In an uncoupling mechanism, the combination with a car coupler and its lock, of means for moving said lock to unlocked position, said means involving a rotatable member operatively connected to said lock and extending rearwardly therefrom, an uncoupling lever, and means for swingingly supporting the rear end of said rotatable member, said supporting means being adapted to swing lengthwise of the car to permit corresponding lengthwise bodily movement of said rotatable member, and said rotatable member being interposed between said uncoupling lever and said supporting means.

6. In an uncoupling mechanism, the combination with a car coupler and its lock, of means for moving said lock to unlocked position, said means involving a rotatable member operatively connected to said lock and extending rearwardly therefrom, an uncoupling lever, and swinging means for supporting said rotatable member rearwardly of said lock, said swinging means being adapted to swing lengthwise of the car and also to turn in response to lateral swinging movement of said rotatable member, and said rotatable member being interposed between said uncoupling lever and said swinging means.

7. In an uncoupling mechanism, the combination with a car coupler and its lock, of means for moving said lock to unlocked position, said means involving a rotatable member operatively connected to said lock and extending rearwardly therefrom, an uncoupling lever, and swinging means for supporting the rear end of said member so as to permit said member to swing in the direction of length of the car, said rotatable

member being interposed between said uncoupling lever and said swinging means.

8. In an uncoupling mechanism, the combination with a car coupler and its lock, of means for moving said lock to unlocked position, said means involving a vertically rotatable member, swinging means for operatively connecting said member to said lock, an uncoupling lever, and swinging means for supporting said member rearwardly of said lock, said last named means being adapted to swing lengthwise of the car responsively to the swinging movement of the said swinging means by which said rotatable member is operatively connected to said lock, and said rotatable member being interposed between said uncoupling lever and said swinging means.

9. In an uncoupling mechanism, the combination with a car coupler and its lock, of means for moving said lock to unlocked position, said means involving a rotatable device which is bodily movable lengthwise of the car, means for operatively connecting said device to said lock, an uncoupling lever, and swinging means supporting said device rearwardly of said lock, said swinging means being adapted to swing lengthwise of the car responsively to lengthwise bodily movement of said device during an unlocking rotation thereof, and said rotatable device being interposed between said uncoupling lever and said swinging means.

10. In an uncoupling mechanism, the combination with a car coupler and its lock, of means for moving said lock to unlocked position, said means involving a rotatable device, a plurality of swinging means for supporting said rotatable device, and an uncoupling lever supported by one of said swinging means through the intermediacy of said rotatable device, said plurality of swinging means being adapted to swing lengthwise of the car and constituting the sole support for said rotatable device.

11. In an uncoupling mechanism, the combination with a car coupler and its lock, of means for moving said lock to unlocked position, said means involving a rotatable member operatively connected to said lock, an uncoupling lever, and means affording a support for said rotatable member rearwardly of said lock, said rotatable member being interposed between said uncoupling lever and said supporting means, and said supporting means being adapted to swing both lengthwise and transversely of the car and to turn in response to angular movement of said rotatable member transversely of the car.

12. In an uncoupling mechanism, the combination with a car coupler and its lock, of means for moving said lock to unlocked position, said means involving a rotatable member operatively connected to said lock,

an uncoupling lever supported at one end by said rotatable member, swinging means for supporting said rotatable member rearwardly of said lock, and means interlockingly connected to said swinging means for supporting the latter.

13. In an uncoupling mechanism, the combination with a car coupler, its lock, a carrier iron and a member slidably mounted on 10 said carrier iron and adapted to be shifted thereon by swinging movement of said coupler, of means for moving said lock to unlocked position, said means involving a rotatable member operatively connected to said lock, means for actuating said rotatable member, and means movably connected to 15 said slidable member and to said rotatable member and adapted to swing lengthwise of the car for supporting said rotatable member.

14. In an uncoupling mechanism, the combination with a car coupler and its lock, of means for moving said lock to unlocked position, said means involving a rotatable member, means for causing said rotatable member to perform an unlocking rotation, and swinging means for permitting the center of rotation of said rotatable member to shift lengthwise of the car, said swinging 30 means engaging and forming a support for said rotatable member, and said rotatable member forming a support for said means for causing an unlocking rotation thereof.

15. In an uncoupling mechanism, the combination with a car coupler and its lock, of means for moving said lock to unlocked position, said means involving a swinging member pivotally connected to said coupler, a link operatively connecting said swinging 35 member and said lock, a vertically rotatable member movably connected to said swinging member, means for actuating said rotatable member, and means for supporting said vertically rotatable member rearwardly of said 40 lock, said last named means being pivotally connected to said rotatable member and being adapted to permit the center of rotation of said rotatable member to shift lengthwise of the car during a lock actuating operation 45 thereof.

16. In an uncoupling mechanism, the combination with a car coupler and its lock, of means for moving said lock to unlocked position, said means involving a swinging member pivotally connected to said coupler, a link movably connected to said swinging member and said lock, a vertically rotatable member provided with oppositely disposed 55 trunnions, a support for said rotatable member, adapted to swing lengthwise of the car, said support having bearings for receiving said trunnions, and a rotatable uncoupling lever which engages and is adapted to actuate said rotatable member.

17. In an uncoupling mechanism, the combination with a car coupler and its lock, of means for moving said lock to unlocked position, said means involving a member pivotally connected to said coupler, a link interposed between said member and said lock, 70 a rotatable member operatively connected to said lock, means for actuating said rotatable member, and swinging means movable lengthwise of the car and pivotally engaging said rotatable member at the center of 75 rotation of the latter for supporting said rotatable member rearwardly of said lock.

18. In an uncoupling mechanism, the combination with a car coupler and its lock, of means for moving said lock to unlocked position, said means involving a swinging member pivotally connected to said coupler, a link operatively connecting said swinging member and said lock, a vertically rotatable member movably connected to said swinging member, means for actuating said rotatable member, and means adapted to swing lengthwise of the car for pivotally supporting 80 said rotatable member at its center of rotation.

19. In an uncoupling mechanism, the combination with a car coupler and its lock, of means for moving said lock to unlocked position, said means involving a swinging member pivotally connected to said coupler, a link movably connecting said swinging member and said lock, a rotatable member operatively connected to said lock, means for actuating said rotatable member, and means adapted to move both lengthwise and transversely of the car for pivotally supporting 95 said rotatable member at its center of rotation.

20. In an uncoupling mechanism, the combination with a car coupler and its lock, of means for moving said lock to unlocked position, said means involving a swinging member pivotally connected to said coupler, a link operatively connecting said swinging member and said lock, a vertically rotatable member movably connected to said swinging member and provided with oppositely disposed trunnions, an uncoupling lever adapted to swing said rotatable member upon its trunnions, and swinging means for supporting said rotatable member rearwardly of said lock, said last named means being provided with a plurality of segmental bearings adapted to receive said trunnions.

21. In an uncoupling mechanism, the combination with a car coupler, its lock and carrier iron, of means for moving said lock to unlocked position, said means involving a vertically rotatable member operatively connected to said lock, means for actuating said rotatable member, and swinging means for supporting said rotatable member, said swinging means being movably connected to 115 120 125

said carrier iron through a hook and eye connection, said eye being elongated transversely of the car.

22. In an uncoupling mechanism, the combination with a car coupler, its lock, a carrier iron and a member slidably mounted on said carrier iron and adapted to be shifted transversely of the car by said coupler, of means for moving said lock to unlocked position, said means involving a swinging member pivotally connected to said coupler,

a link operatively connecting said swinging member and said lock, a vertically rotatable member movably connected to said swinging member, an uncoupling lever engaging and adapted to actuate said vertically rotatable member, and swinging means movably connected to said slidably member and to said rotatable member for supporting the latter.

In testimony whereof I affix my signature.

WILLIAM KELSO.
